EDWARD N. MOOR, OF OAKLAND, CALIFORNIA

TRAVERSE GRINDING, MILLING, AND DRILLING MACHINE FOR LATHES.

1,073,698.

Specification of Letters Patent. Patented Sept. 23, 1913.

Application filed January 29, 1913. Serial No. 744,884.

To all whom it may concern:

Be it known that I, EDWARD N. MOOR, a citizen of the United States, residing at Oakland, in the county of Alameda and 5 State of California, have invented certain new and useful Improvements in Traverse Grinding, Milling, and Drilling Machines for Lathes, of which the following is a specification.

10 My invention relates to the general class of lathe-attachments, and particularly to traverse machines adapted for such work as grinding, milling, drilling, etc.

The object of my invention is to provide 15 a rigid, economically constructed and adjustably efficient traverse machine of this class, and to this end my invention consists in the novel machine and in the construction, arrangement and combination of 20 its parts which I shall now fully describe by reference to the accompanying drawings, in which—

Figure 1 is a front elevation of my machine. Fig. 2 is an end elevation, partly 25 broken, of the same, the spindle in the carrier being omitted. Fig. 3 is a section on the line $\alpha-\alpha$ of Fig. 2.

1 is a rigid column which forms the stock 30 of the machine. Through a central longitudinal bore of said column is fitted a bolt 2, the lower projecting end of which is formed with a foot flange 3 and its upper threaded end is fitted with a nut 4 which bears on a cap 5 on the head of the column-stock. By referring to Fig. 2 it will be 35 seen that the column-stock is rigidly clamped to and carried by the lathe tool-post support 6, (sufficiently indicated in dotted lines) by the foot flange 3 of the 40 bolt 2 fitting the slot of said support, and by means of the nut 4, clamping the support between said flange and the column foot. Thus the whole machine is firmly 45 clamped to the tool-post support, and may be readily fitted to place and removed; and by reason of the rigidity of the column, the whole device is rigid and stable.

About the column-stock 1 on a spline or feather 7 thereon, as seen in Figs. 2 and 50 3, is fitted the split sleeve 8, adapted for accurate lineal movement or adjustment and to be rigidly fixed in the position to which it is adjusted, by means of a bolt 9, Fig. 3, through its meeting ears 10 at its 55 split extremities. The sleeve 8 when

loosened for movement by relieving its bolt 9, is adjusted with facility and accuracy, by means of a screw 11. This screw, as seen in Fig. 2, has a handle 12 on its upper end, said end being seated in a lug 13 projecting from the cap 5 of the column stock and fitted with clamping nuts 14. The screw 11 is threaded through a nut 15 of the sleeve 8, and its lower end finds a footing in a lug 16 projecting from the foot of the column 60 stock. In order to define and accurately read the extent of the vertical or lineal adjustment of the sleeve 8, said sleeve is fitted with a pointer 17, as shown in Fig. 2, said pointer being itself adjustably carried in a 65 socket bearing 18 on the side of the sleeve and secured where adjusted by a set screw 19. The pointer 17 coacts with a vertical scale or line of graduations 20 on the column stock to afford the necessary readings. 75

The front of the sleeve 8 is formed with a boss 21 having a reduced portion 22, as shown in Fig. 3. Upon this reduced portion is fitted and adapted to be turned for angular adjustment the annular body 23 of 80 the spindle carrier 24. The carrier body 23 and the reduced portion 22 of the sleeve boss 21 have fitted to their faces the gage plate 25, the peripheral edge of which has angle-graduations 26, as seen in Fig. 2. A 85 bolt 27 clamps these several parts together and fixes them rigidly in position. When the bolt 27 is loosened, the carrier 24 may be turned to an angular adjustment, the amount of which is readable on the graduations 26. The gage plate 25 is anchored to the boss 21 by an anchor screw 28, shown in Fig. 1, and in dotted lines in Fig. 2.

The spindle carrier 24 is a split sleeve clamped by bolts 29 through its ears 30. 95 In this carrier are mounted the spindle, the bushings, the chucks, the draw-in rod and such other parts as are usual. For the sake of illustration, I show in Fig. 1, the spindle 31, with its belt pulley 32, the bushing 33, the chuck 34 with its grinder 35, and the draw-in rod 36 with its handle 37. These parts illustrate a grinding machine though it must be understood that for other work, such as milling, drilling, etc., the proper 105 tools will be substituted for the grinder.

38 in Fig. 1 indicates an oil cup connection.

The upper portion of the carrier body 23 is formed with a split bearing 39 clamped 110

by bolts 40. This bearing is used for holding devices which form no part of the present application.

I claim:—

5. 1. A traverse machine for lathes, comprising a column-stock with means for securing it to the lathe-member; a sleeve encircling and feathered on said column-stock for lineal movement, said sleeve having means for 10 fixing it on the column stock in adjusted position; means carried by the stock for lineally moving the sleeve; a spindle carrier carried by said sleeve; a tool-operating spindle in said carrier; and driving means 15 carried by the spindle.

2. A traverse machine for lathes, comprising a column-stock with means for securing it to the lathe-member; a sleeve encircling and feathered on said column-stock 20 for lineal movement, said sleeve having a nut and having also means for fixing its position on the column-stock; a screw carried by the stock and engaging the sleeve nut for lineally moving the sleeve; a spindle-carrier 25 carried by said sleeve; a tool-operating spindle in said carrier; and driving means carried by the spindle.

3. A traverse machine for lathes, comprising a column-stock, having a cap-plate; 30 a bolt passing through said cap plate and longitudinally through the stock and having a foot-flange adapted to engage the lathe-member, said bolt having a nut for tightening the stock to said member; a split sleeve 35 encircling and feathered on said stock for lineal movement, said sleeve having a clamping bolt for fixing it on the stock and having also a nut; a screw carried by the cap of the column stock and provided with 40 clamping nuts, said screw engaging the sleeve nut for lineally moving the sleeve; and a spindle-carrier carried by said sleeve.

4. A traverse machine for lathes, comprising a column-stock with means for securing it to the lathe-member; a sleeve encircling said stock and feathered thereon 45 for lineal movement; means for lineally moving the sleeve and means for fixing it where adjusted; a pointer carried by the sleeve coacting with graduations on the stock 50 for indicating the lineal adjustment of said sleeve; a spindle-carrier carried by said sleeve; a tool-operating spindle in said carrier; and driving means carried by the 55 spindle.

5. A traverse machine for lathes, comprising a column-stock with means for securing it to the lathe-member; a sleeve encircling said stock and feathered thereon 60 for lineal movement; means for lineally moving the sleeve and means for fixing it where adjusted; a pointer carried by the sleeve coacting with graduations on the stock 65 for indicating the lineal adjustment of said sleeve; said pointer being mounted for in-

dependent lineal adjustment; and a spindle-carrier carried by said sleeve.

6. A traverse machine for lathes, comprising a column-stock with means for securing it to the lathe-member; a sleeve encircling said stock and feathered thereon 70 for lineal movement; means for lineally moving the sleeve and means for fixing it where adjusted; a spindle-carrier having a body rotatably mounted on the sleeve for 75 angular adjustment, means for fixing the spindle-carrier in the position to which it is adjusted; a tool-operating spindle in said carrier; and driving means carried by the spindle.

7. A traverse machine for lathes, comprising a column-stock with means for securing it to the lathe-member; a sleeve encircling said stock and feathered thereon 85 for lineal movement; means for lineally moving the sleeve and means for fixing it where adjusted; a boss of said sleeve; a spindle-carrier having a body rotatably mounted on the boss for angular adjustment; a plate for clamping the carrier body 90 on the boss; and a bolt clamping the plate, body and boss together.

8. A traverse machine for lathes, comprising a column-stock with means for securing it to the lathe-member; a sleeve encircling said stock and feathered thereon 95 for lineal movement; means for lineally moving the sleeve and means for fixing it where adjusted; a boss of said sleeve; a spindle-carrier having a body rotatably mounted on 100 the boss for angular adjustment; a plate for clamping the carrier body on the boss, said plate having graduations on its periphery; a bolt clamping the plate, body and boss together; and a bolt anchoring the 105 plate to the boss.

9. A traverse machine for lathes, comprising a column-stock; a longitudinal bolt for securing it to the lathe member; a sleeve encircling said stock and feathered thereon 110 for lineal movement, said sleeve having a bolt for clamping it in position on the stock and having also a nut; a screw carried by the stock and engaging the sleeve nut for lineally moving said sleeve; a boss of said 115 sleeve; a spindle-carrier having a body rotatably mounted on the boss for angular adjustment; a plate for clamping the carrier body on the boss; a bolt clamping the plate, body and boss together; a tool-operating spindle in said carrier; and driving means carried by the spindle.

10. A traverse machine for lathes, comprising a column-stock; a longitudinal bolt for securing it to the lathe member; a sleeve encircling said stock and feathered thereon 125 for lineal movement, said sleeve having a bolt for clamping it in position on the stock and having also a nut; a screw carried by the stock and engaging the sleeve nut for 130

lineally moving said sleeve; an adjustable pointer carried by the sleeve and coacting with graduations on the stock for indicating the lineal adjustment of said sleeve; a boss of said sleeve; a spindle-carrier having a body rotatably mounted on the boss for angular adjustment; a plate for clamping the carrier body on the boss; said plate having graduations on its periphery; a bolt clamping the plate, body and boss together; 10 and a bolt anchoring the plate to the boss.

In testimony whereof I have signed my name to this specification in the presence of two subscribing witnesses.

EDWARD N. MOOR.
